UNITED STATES PATENT OFFICE.

WILLIAM BOEKEL AND JULIUS BOEKEL, OF PHILADELPHIA, PENNSYLVANIA.

MERCURY TEST-GAGE.

SPECIFICATION forming part of Letters Patent No. 559,767, dated May 5, 1896.

Application filed April 29, 1893. Serial No. 472,426. (No model.)

To all whom it may concern:

Be it known that we, WILLIAM BOEKEL and JULIUS BOEKEL, citizens of the United States, residing at Philadelphia, in the county of Philadelphia and State of Pennsylvania, have invented certain new and useful Improvements in Plumbers' Mercury Test-Gages; and we do declare the following to be a full, clear, and exact description of the invention, such 10 as will enable others skilled in the art to which it appertains to make and use the same, reference being had to the accompanying drawings, and to the letters of reference marked thereon, which form a part of this specification.

Our invention relates to plumbers' mercury test-gages, which, as heretofore constructed, have had the following objections: First, the mercury is placed in an air-chamber at the 20 top of the gage, allowing the mercury, when spilled, to get into the lower parts of the gage, which are constructed of brass, thereby destroying them; second, after using the gage the mercury has to be poured out of the air-chamber into a bottle or receptacle, which 25 may break or be mislaid.

The object of our invention is to overcome these objections and also to protect the gage-tube when the mercury-cup has been removed.

We attain this object by means of the mechanism illustrated in the following drawings, in which—

Figure 1 is an end elevation of the gage with a portion in section. Fig. 2 is a plan 35 with the three-way cock in section. Fig. 3 is a similar view with the cock in a different position and some of the parts omitted. Fig. 4 is an elevation of the mercury-cup, showing 40 it sealed up after being removed. Fig. 5 is the guard for the glass tube with the mercury-cup removed. Fig. 6 is another view of the gage, partly in section.

a is a mercury-cup screwed into the body *b* of the gage, the joint being made air-tight 45 by the washer *a'* or in any ordinary manner, and the lower portion of the mercury-cup is enlarged to form the chamber *a''* to hold the mercury *d*. The inlet or mouth of the mercury-cup is larger in diameter than the glass 50 tube *c* to allow the air to pass downward into the chamber *a''* to act upon the mercury *d* to force it upward into the tube *c* to indicate the

pressure. The body *b* is enlarged to allow the air which is admitted through the passage-way *b'* to circulate around the tube *c*. 55 The gland *g* is screwed into the body *b* against the washer *g'*, making an air-tight joint around the glass tube *c*. The guard *g'* is secured to the gland *g* and is provided with the opening *g''* to expose to view the position of the mercury as it ascends the tube *c*, indicating the 60 pressure.

h is a two-way cock for controlling the air as it comes from the pump through hose *l*, which is connected to the body *b* by means 65 of the coupling *s'*.

m is a short section of the pipe to be tested.

The two-way cock *h* is located between the inlet *b''*, outlet *b'*, and the mercury-cup *a* at the intersection of the passage-ways *b''* *b'* *b'*, 70 as shown in Fig. 2. When the cock *h* is turned in the position shown in Fig. 2, the air passes from the inlet *b''* through the passage-ways *b''* *b'* into the pipe *m*. When turned to the position shown in Fig. 3, the air is shut off from 75 the inlet and is allowed to pass from the pipe *m* through passage-ways *b''* *b'* into the mercury-cup *a* to force the mercury up the glass tube *c* to indicate the pressure.

o is the ether-cup to introduce ether into 80 the pipe being tested.

When the gage is not in use, the mercury-cup is removed and sealed by the cap *a''*, as shown in Fig. 4, and can be carried in the tool-box, avoiding any loss from the pouring 85 of the mercury into a bottle or by its breakage. The piece of pipe or tube *p*, Fig. 5, is then screwed into the body *b* of the gage to take the place of the mercury-cup just removed and to protect the glass tube *c*, which 90 is exposed by the removal of the mercury-cup, thereby allowing the gage to be carried in a tool-box. It is obvious that the mercury being in the mercury-cup below the other parts of the gage, it is not possible for any of it to 95 pass out of the cup to injure the parts.

The construction of our gage may be greatly varied and not depart from the spirit of our invention.

What we claim as our invention is—

1. In a mercury test-gage, the mercury-cup *a* having a screw-threaded upper part, in combination with a tubular body screw-threaded for engagement therewith, means for direct-

ing a current of air through the said body into the said mercury-cup at will, and a gage-tube extending down into the said mercury-cup, substantially as and for the purpose set forth.

2. In a mercury test-gage, the combination of a tubular body screw-threaded at its lower end with a gage-tube inside of the said body and extending below its lower end and a detachable piece adapted to be screwed on the lower end of the said body as a substitute for

the mercury-cup for the purpose of protecting the protruding part of the gage-tube when the said cup has been removed, substantially as set forth.

In testimony whereof we affix our signatures in presence of two witnesses.

WILLIAM BOEKEL.

JULIUS BOEKEL.
